UNITED STATES PATENT OFFICE

HEINRICH KELLERMANN, OF BERLIN-LICHTENBERG, GERMANY

PYROPHORIC LIGHTER

Application filed August 7, 1930, Serial No. 473,625, and in Germany September 2, 1929.

The present invention relates to a pyrophoric lighter of that kind, in which the wheel file and the carrier of the wick-cap or 5 the snuffing cap are placed upon a common axle of rotation, both parts being so coupled with each other, that upon rotation of the carrier of the wick-cap during the opening movement the wheel file is taken along, whereby 10 sparking particles are scraped from the pyrophoric mass pressed against the wheel file, the produced sparks being directed upon the end of the wick disposed beside said wheel file.

Known lighters of this kind show the 15 drawback, that the speed of the opening movement of the snuffing cap, and with it the speed of rotation of the wheel file, determining the intensity of the spark production, is entirely dependent upon the intensity 20 of the pressure exercised by the hand or the finger of the user upon the snuffing cap or upon the parts connected therewith. It has, it is true, already been proposed, to place the 25 opening movement of the snuffing cap under the action of a spring, so that the speed of that movement is made dependent upon the intensity of tension of this spring. In this case, however, the arrangement was of such 30 nature, that the finger starting that movement easily hindered the further movement of the snuffing cap under the influence of that spring, with the result that the spring tension could not fully develop, and the 35 speed of rotation of the file was interfered and hindered too.

For the purpose of avoiding these drawbacks, the arrangement in accordance with the present invention is such, that the snuffing cap is pivotally connected to the pressure lever, with the aid of which the lighter is 40 actuated by means of a bridge which is joined with the snuffing cap at a point situated between the axle of rotation of the latter and the wick-tube, said bridge being under the influence of a spring. Upon actuating the pressure lever with the aid of the finger, the spring, after overcoming a dead point 45 position, suddenly throws back the snuffing cap into the open position quite independent 50 of the speed and of the intensity of the fin-

ger-pressure, thereby causing the wheel file to rapidly revolve.

The lighter may also be constructed, if desired, in such a manner that after the opening of same and the generation of sparks has been effected, it will be automatically closed through the action of a second spring provided for that purpose, upon releasing the mold upon the pressure lever.

In the drawings the object of the invention has been represented by way of example.

Fig. 1 is a lateral view of an example of performance of the lighter in the closed position,

Fig. 2 a view of the same lighter in the open position, part of the front wall of the casing being broken away,

Fig. 3 represents a modified form of performance in lateral view in the closed position with part of the casing wall being broken away.

Figs. 4-6 are lateral views of a third embodiment in the closed position, partly in section, at the commencement of the opening movement, and in open position.

Figs. 7-11 represent details of the construction in accordance with Figs. 4-6.

In the example of execution shown in Figs. 1 and 2, 1 is the casing of the lighter, 2 the end of the wick-tube, 4 the carrier of the wick-cap or the snuffing cap and 3 the wick-cap proper. The axle of rotation 5 of the snuffing cap 4 is arranged in a support 7. This axle 5 may be made to consist of a screw or double screw capable of being easily removed. The axle 7 also carries the wheel file 6, against which the pyrophoric pin is pressed from below in the usual manner and which may be coupled in any desired known manner with the snuffing cap or wick-cap carrier 4.

At 9 an arcuated arm or bridge 8, extending rearwardly, has been articulated to the snuffing cap 4. This arm or bridge 8 carries at its rearward end a cylindrical sleeve 13 being attached thereto by means of a hinge at 14, said cylindrical sleeve 13 containing a pressure spring 15. The lower end of this pressure spring 15 is resting upon a transverse pin 16, which penetrates into the open lower end 100 of the sleeve 13 through a guide slot 17.

The transverse pin 16 is arranged within a cap-shaped double armed pressure lever 11, its point of rotation being situated at a transverse pin 18 passing through the casing 1 of the lighter. This transverse pin 18 is embraced by the pressure lever 11 by means of a hook 19 in such a manner, that it may easily be released. The arcuated arm or bridge 8 is pivotally connected at 10, midway between its two ends, with the pressure lever 11. The pivot point 9 of this arm 8 at the wick-cap carrier 4 is so disposed, that the pivot point 9, when the lighter is in the closed position (Fig. 1), will be at a place situated between the vertical transverse plane passing through the axle of rotation 5 and the parallel vertical plane passing through the wick-tube 2, whilst, when opening the lighter, this pivot point 9 wanders through said first named vertical plane in a rearward direction, as may be gathered from Fig. 2.

The operation of this lighter is as follows:

If the parts are in the closing position as seen from Fig. 1, the spring 15, resting upon the transverse pin 16, presses the rear end of the arcuated arm or bridge 8 upwards, correspondingly pressing the carrier 4 of the wick-cap downwards, i. e. against the wick-tube 2. If now pressure by a finger is exercised upon the rearward extension 12 of the pressure-lever 11, so that it begins to revolve round the axis 18 in a rearward direction, the snuffing cap 4 will in the first instance be taken along against the action of the spring 15 by means of the bent arm or bridge 8 forming the connecting link, until the pivot point 9 has crossed the vertical plane passing through the axis of rotation 5. Hereafter owing to the changed position of the sleeve 13 and the spring 15 disposed within said sleeve, the spring no longer exercises a pressure in an upward direction, but in a rearward direction, and has, for this reason, the tendency to open the cap 4, in extending itself. This opening movement of the part 4 in conjunction with the rotation of the extending spring 15 and with it the further rotation of the wheel file 6 taken along, takes place, after overcoming the dead point position for the pivot 9, rapidly and suddenly, quite independently of the speed of the movement of the finger or the intensity of the pressure of the finger, so that the wheel file 6 revolves with corresponding speed, thus producing sparks of considerable intensity by its contact with the pyrophoric mass. The closing of the lighter is effected in this example of execution by turning the snuffing member 4 by hand causing the parts 8 and 11 connected with the member 4 to be taken along and returned into the closing position (Fig. 1).

The form of construction shown in Fig. 3 is distinguished from that just described essentially only by that, for the purpose of simplifying the construction of the lighter,

the pressure lever 11 has been omitted. In this case the opening of the lighter is effected by pressing the finger from below against a shoulder or handle 20, being attached to the snuffing member 4, so that the member 4 is caused to turn round the axis 5. For the purpose of preventing the bent arm or bridge 8 from being moved upwards instead of backwards, it is provided, at 22 with a movable arm 21, the lower end 24 of which forms a hook embracing a transverse pin 23 passing through the casing 1 of the lighter. This transverse pin 23 takes in this case the place of the transverse pin 16 provided in the pressure-lever 11 of the first described form of construction and thus also forms the lower stop for the pressure spring placed within the slotted sleeve 13. The operation for this construction essentially resembles that of the lighter shown in Figs. 1 and 2.

In the form of construction shown in Figs. 4 to 11, the disposition and construction of the snuffing cap or wick-cap carrier and of the wheel file is again the same as in the cases previously described. The pressure-lever 11, too, is essentially of the same construction and disposition as in the form shown in Figs. 1 and 2. The arm or bridge 25 extending in a rearward direction in this case, too, is pivoted to the snuffing cap 4 at a point 26, which is situated between the vertical transverse planes passing through the axis of rotation 5 and the wick-tube 2. The arm 25 here is provided at its rearward end with an oblong slit or a notch 27, in which a transverse pin 28, passing through the pressure lever 11, can be made to glide to and fro.

At 26, moreover, the upper end of a U-shaped arm 29 is pivotally attached, whereas its lower end is pivotally connected at 30 with the inner part 42 of a divided cylindrical sleeve. The inner part 42 of the sleeve has the shape of a frame. If the gap 44 of this frame-like inner sleeve-part 42 the spring 35' is arranged. The part 42 is provided at its lower end with a pin-like extension 43 and beside this with a shoulder or stop 49.

The frame-like inner sleeve-part 42 for the spring 35' is embraced by a fork-like or U-shaped outer sleeve-part 45. This has been illustrated in the Figures 10 and 11 separately in two side views seen in an angle of 90° to one another. The sleeve-part 45 embraces with its gap 46 (Fig. 11) the inner sleeve-part 42, and it possesses a lower extension 47 provided with a passage for the pin 43. Next to the extension 47 a stop 48 is arranged. Through an opening near the upper end of the sleeve-part 45 a pin 34 (Fig. 7) has been made to pass, which also passes transversely through the gap 44 of the inner sleeve-part 42, forming here one of the stops for the spring 35', its other stop being formed by the bottom of the frame 42. The

pin 34 simultaneously connects the sleeve part 45 pivotally with the pressure-lever 11.

Against the stop 48 of the outer sleeve part 45 a stronger spring 38 is made to rest, the second stop of which is formed by the bottom of a tube 39 closed at the lower end, said tube 39 also forming a cover for the sleeve 42, 45.

The operation of the device is illustrated by the Figures 4-6. When the lighter is closed, the parts will be in the position shown in Fig. 4. Both springs 35' and 38 are free or nearly free from tension and jointly cause the snuffing cap 4 to be restrained in the closing position, i. e. cause it to be forced against the wick-tube 2. If it is desired to open the lighter, pressure is exercised by the finger upon the rearward lug or shoulder 12 of the pressure-lever 11. This lever in the first instance describes the movement which may be seen from Fig. 5, during which the outer sleeve-part 45, being connected with the lower extension of the pressure-lever 11 by means of the pin 34, is already pressed downward a little against the action of the spring 38, so that the outer spring 38 and also the spring 35' in the inner sleeve-part 42 are already slightly compressed, whilst the snuffing cap 4 still remains in the closing position as the pin 28 may slide in the notch 27. Upon further movement of the pressure lever 11 the spring 35' is compressed to such an extent, that the pivot point 26 for the bridge 25 and the arm 29 on the snuffing cap 4 has crossed the dead point position, i. e. has passed through the vertical transverse plane going through the axis 5 of the wheel file 6. The spring 35' will then be able to act against the bent arm 29 of the bridge, thereby throwing it, and with it the snuffing cap 4, in a rearward direction, i. e. in the open position, whilst the spring 38, owing to the pressure exerted on the lever 11 and with it upon the outer sleeve part 45, will be further compressed, so that it cannot counter-act the action of the weaker spring 35'. The opening of the snuffing cap 4 therefore is effected under the action of the spring 35' when the dead-point position has been passed under the action of the spring 35', and this opening movement is performed automatically, rapidly and independently of the intensity and speed of the finger-pressure exercised, and corresponding thereto the rotation of the wheel file 6 during this part of the movement takes place rapidly and strongly, so that intensive sparks are produced by the friction against the pyrophoric mass.

Upon releasing the pressure-lever 11 the parts will return from the position shown in Fig. 6 to their original position shown in Fig. 4 under the action of the extending stronger spring 38, this closing of the lighter thus being performed automatically.

In all examples of performance shown the

parts belonging to the mechanism of the lighter, i. e. the snuffing cap together with the wheel file, the bent arm or bridge, the spring-sleeve and the spring and also, if desired, the pressure-lever, are arranged in such a manner that they may easily be removed and substituted, because, on the one hand, the axle 5 may be easily removed and, on the other hand, the pressure-lever 11 and the arm 21 (Fig. 3) are merely hooked to their axle.

Various modifications of the devices as shown and described may be made within the scope of the invention.

Having now particularly described and ascertained the nature of my said invention, I declare that what I claim is:

1. A pyrophoric lighter comprising a wick-tube, a wheel file, a snuffing member, a common axis for said wheel file and snuffing member, said snuffing member being coupled with said wheel file, a pressure-lever, means hingedly connecting said snuffing member to said pressure lever, said means engaging said snuffing member at a point situated between two vertical transverse parallel planes when the snuffing member is in the closed position, one of which planes passes through the pivot axle of said snuffing member and the other of said planes passing through the wick-tube, a spring acting upon said means, said spring being arranged in such a manner, that upon operating said pressure-lever by hand said snuffing member is suddenly thrown back into the open position after the dead point position has been overcome, independently of the speed and intensity of the pressure of the finger.

2. A pyrophoric lighter comprising a wick-tube, a wheel file, a snuffing member, a common axis for said wheel file and snuffing member, said snuffing member being coupled with said wheel file, a pressure-lever, a link hingedly connecting said snuffing member to said pressure lever, said link engaging said snuffing member at a point situated between two vertical transverse parallel planes when the snuffing member is in the closed position, one of which planes passes through the pivot axle of said snuffing member and the other of said planes passing through the wick-tube, a spring acting upon said link, said spring engaging a rearward extension of said link in such an angular position, that said snuffing member is thereby forced into the closing position, as long as the pivot point of said link has not reached the dead-point position.

3. A pyrophoric lighter comprising a wick-tube, a wheel file, a snuffing member, a common axis for said wheel file and snuffing member, said snuffing member being coupled with said wheel file, a pressure-lever, means hingedly connecting said snuffing member to said pressure lever, said means engaging said snuffing member at a point situated between two vertical transverse parallel planes when

the snuffing member is in the closed position, one of which planes passes through the pivot axle of said snuffing member and the other of said planes passing through the wick-tube, a spring acting upon said means, a sleeve surrounding said pressure-spring said sleeve being open below, the upper end of said sleeve being hingedly connected to said bridge, a stop for said spring, said stop engaging the lower end of said sleeve, said spring and sleeve being arranged in such a manner, that upon operating said pressure-lever by hand said snuffing member is suddenly thrown back into the open position after the dead point position has been overcome, independently of the speed and intensity of the pressure of the finger.

4. A pyrophoric lighter comprising a wick-tube, a wheel file, a snuffing member, a common axis for said wheel file and snuffing member, said snuffing member being coupled with said wheel file, a pressure-lever, a bridge hingedly connecting said snuffing member to said pressure lever, said bridge engaging said snuffing member at a point situated between two vertical transverse parallel planes when the snuffing member is in the closed position, one of which planes passes through the pivot axle of said snuffing member and the other of said planes passing through the wick-tube, a spring acting upon said bridge, a sleeve surrounding said pressure-spring, said sleeve being open below, the upper end of said sleeve being hingedly connected to said bridge, a transverse pin provided at the lower part of said pressure-lever, said transverse pin serving as a stop for said pressure-spring, the lower end of the said sleeve being slotted for allowing the passage of said transverse pin, said spring and sleeve being arranged in such a manner, that upon operating said pressure-lever by hand said snuffing member is suddenly thrown back into the open position after the dead point position has been overcome, independently of the speed and intensity of the pressure of the finger.

5. A pyrophoric lighter comprising a wick-tube, a wheel file, a snuffing member, a common axis for said wheel file and snuffing member, said snuffing member being coupled with said wheel file, a pressure-lever, a bridge hingedly connecting said snuffing member to said pressure lever, said bridge engaging said snuffing member at a point situated between two vertical transverse parallel planes when the snuffing member is in the closed position, one of which planes passes through the pivot axle of said snuffing member and the other of said planes passing through the wick-tube, a spring acting upon said bridge, a second stronger spring acting upon the rearwardly extending arcuated extension of said bridge in such a manner, that it tends to always force said snuffing member into the closing position as long as the lighter is not

operated, whilst said stronger spring is thrown out of action by the finger pressure exerted upon said pressure lever during the operation of the lighter, said first named weaker spring being arranged in such a manner, that upon operating said pressure-lever by hand said snuffing member is suddenly thrown back into the open position after the dead point position has been overcome, independently of the speed and intensity of the pressure of the finger.

6. A pyrophoric lighter comprising a wick-tube, a wheel file, a snuffing member, a common axis for said wheel file and snuffing member, said snuffing member being coupled with said wheel file, a pressure-lever, a bridge hingedly connecting said snuffing member to said pressure lever and having a rearwardly extending arcuate extension, said bridge engaging said snuffing member at a point situated between two vertical transverse parallel planes when the snuffing member is in the closed position, one of which planes passes through the pivot axle of said snuffing member and the other of said planes passing through a wick-tube, two springs, a weaker and a stronger one, said stronger spring acting upon said rearwardly extending arcuate extension of said bridge, a divided sleeve, said divided sleeve surrounding said weaker spring, one part of said divided sleeve being hingedly connected to said pressure lever, the other part of said sleeve being hingedly connected to said snuffing member, said stronger spring being arranged in such a manner, that it tends to always force said snuffing member into the closing position as long as the lighter is not operated, whilst said stronger spring is thrown out of action by the finger pressure exerted upon said pressure lever during the operation of the lighter, said first named weaker spring being arranged in such a manner, that upon operating said pressure-lever by hand said snuffing member is suddenly thrown back into the open position after the dead point position has been overcome, independently of the speed and intensity of the pressure of the finger.

7. A pyrophoric lighter comprising a wick-tube, a wheel file, a snuffing member, a common axis for said wheel file and snuffing member, said snuffing member being coupled with said wheel file, a pressure-lever, a bridge hingedly connecting said snuffing member to said pressure lever and having a rearwardly extending arcuate extension, said bridge engaging said snuffing member at a point situated between two vertical transverse parallel planes when the snuffing member is in the closed position, one of which planes passes through the pivot axle of said snuffing member and the other of said planes passing through the wick tube, two springs, a weaker and a stronger one, said stronger

spring acting upon said rearwardly extending arcuate extension of said bridge, a divided sleeve, said divided sleeve surrounding said weaker spring, one part of said divided sleeve being hingedly connected to said pressure lever, the other part of said sleeve being hingedly connected to said snuffing member, said stronger spring embracing said divided sleeve for said weaker spring, a stop arranged on one of the parts of said divided sleeve, said stronger spring pressing from below against said stop.

8. In a lighter in accordance with claim 5, said divided sleeve having an inner part for receiving said weaker spring, an arcuated arm hingedly connected to said snuffing member, said inner sleeve-part being pivotally connected with said arcuated arm, a stop for said weaker spring on the outer sleeve-part, said stop penetrating into said inner sleeve-part, said outer sleeve-part being movably arranged on the inner sleeve-part.

9. In a lighter in accordance with claim 5, said means consisting of two parallel arms, both said arms engaging said snuffing member at the same point, and one of said parallel arms being provided with a rearward extension for the engagement with both said springs, the rearward end of said other arm engaging said pressure lever.

30 In testimony whereof I have hereunto set my hand.

HEINRICH KELLERMANN.
